(57) **CLAIM**

The ornamental design for an educational poster, as shown and described.

DESCRIPTION

Copies of this patent or patent application publication with color drawing(s) will be provided by the Office upon request and payment of the necessary fee. Reference is made to the accompany drawing which forms a part hereof, the FIGURE of which is described as follows:

The sole drawing FIGURE is a front elevational view of the educational poster. The design of the educational poster is printed on flat material.

1 Claim, 1 Drawing Sheet
